UNITED STATES PATENT OFFICE

WILLIAM H. MINER, OF CHAZY, NEW YORK, ASSIGNOR TO W. H. MINER, INC., OF CHICAGO, ILLINOIS, A CORPORATION OF DELAWARE

CAR CONSTRUCTION

Application filed July 14, 1928. Serial No. 292,891.

This invention relates to improvements in car construction.

One object of the invention is to provide means for connecting the body bolster of a car to the cooperating truck bolster in such a manner that accidental separation of the same is prevented, wherein the connecting means includes a center pin provided with a sectional, detachable locking head member, having the sections thereof seated in a pocket of the cooperating bolster to retain the same engaged with the pin, one of the walls of the pocket being cut away to provide a removable wall section, the cut-away portion permitting insertion of the sections of the head and assembling of the same with the pin, and a locking key forming a detachable wall section insertible in said cutway portion, the locking key being secured to one of said sections to prevent removal of the key.

Other and further objects of the invention will more clearly appear from the description and claims hereinafter following.

In the drawing, forming a part of this specification, Figure 1 is a top plan view of the central section of the body bolster member of a railway car, illustrating my improvements in connection therewith. Figure 2 is a longitudinal, vertical sectional view of the body bolster and cooperating truck bolster member, corresponding substantially to the line 2-2 of Figure 1. And Figure 3 is a detailed perspective view of one of the sections of the locking head.

In said drawings, 10 designates the body bolster of a railway car underframe structure and 11 the cooperating truck bolster member. The body bolster 10 is provided with a downwardly projecting bearing section 12, which cooperates with a bearing block 13 supported on the truck bolster member 11. The block 13 is disposed within the usual pocket 14 provided at the top of the member 11. The bearing members 12 and 13 are provided with cooperating spherical bearing surfaces and the member 13 has an upstanding central projecting portion 15 which engages within the recess at the center of the bearing member 12.

In carrying out my invention, I provide

the bolster members 10 and 11 with aligned center pin receiving openings 16 and 17. The body bolster member is provided with a pocket 18 at the top thereof, the pocket being centrally aligned with the pin receiving opening 16 and having an offset section 19 providing a key receiving seat. As clearly shown in Figures 1 and 2, the pocket is of greater diameter than the corresponding pin receiving opening 16, so to accommodate the sections of the sectional head B, as herein-after more clearly pointed out.

The truck bolster 11 is provided with a pocket 20 at the bottom thereof, which is in alignment with the opening 17 and is adapted to accommodate the head of the center pin.

My improved center pin locking arrangement proper comprises a pin member A, a sectional head B, and a cooperating locking key C, which is attached to one of the sections of the head B by a cotter pin D.

The center pin A extends through the openings 16 and 17 of the body and truck bolster members and, as shown, the shank thereof is of appreciably smaller diameter than the openings. At the bottom end, the pin A is provided with an integral head 21 which fits within the pocket 20 and has shouldered engagement with the top wall of said pocket. At the upper end, the pin A is provided with a head 22 of smaller diameter than the head 21, the head 22 being of such a size as to be passed freely through the pin receiving openings of the truck and body bolsters. The head 22 provides an annular shoulder at the bottom side thereof, which serves as anchoring means for the sections of the detachable head B, as herein-after pointed out.

The sectional head B comprises four members, one of which is shown in detail in Figure 3. Each of the sections comprises a curved wall portion 23 having an inwardly extending, horizontal flange 24 at the bottom thereof. The four sections, when assembled, form a complete annulus. As clearly shown in Figure 1, the offset section 19 of the pocket 18 of the body bolster corresponds in length to one of the sections of the head B and is of such a width as to provide a seat

to permit insertion of one of the sections of the head B, so that the flange 24 at the bottom of said section will clear the head 22 of the pin. As shown in Figure 2, the head 22 of the pin is so disposed as to leave clearance between the same and the bottom wall of the pocket 18 to accommodate the flange portions 24 of the sections of the head B.

The key member C is in the form of a heavy curved plate which occupies the offset section of the pocket 18 and is adapted to fit snugly between the outer wall of said offset section and the adjacent section of the head B. As shown in Figure 2, the sections of the head B and the key C are of greater height than the head 22 of the pin, and the key and the adjacent section are perforated to accommodate the cotter pin D, by means of which the key is locked to said section, the inner end of the cotter pin being accommodated above the head 22 of the center locking pin A.

In applying my improved center pin construction to the body and truck bolsters of a car, the pin is inserted from the bottom side of the truck bolster, the shank of the pin being passed through the openings 17 and 16 of the truck and body bolsters, respectively. When the pin proper has been placed in this position, one of the sections of the head B is inserted within the offset seat portion of the pocket 18 and then moved laterally inwardly to engage the flange 24 thereof beneath the head 22 of the pin. The section which has been applied is then rotated to dispose the same between the curved wall of the pocket and the head 22 of the pin, to one side of the offset section of said pocket. The remaining sections of the head B are then assembled in a similar manner until the last section is placed in position. When the last section has been placed in position with the flange thereof engaged beneath the head 22 of the center locking pin, the key C is inserted within its seat, the key forming in effect a detachable wall section of the pocket 18.

As will be evident, when the key C is in position, the sections of the head B will be embraced in their entirety by the wall of the pocket, including the detachable wall section, thereby preventing detachment of the sections of the head from the head 22 of the center locking pin. In order to prevent accidental removal of the key forming the detachable wall section, the cotter pin D is then inserted through the openings in the key and the section of the head B last applied and secured in position, thereby permanently attaching the key to the removable sectional head B and preventing removal of said key.

As will be evident, endwise removal of the center pin A in both directions will be prevented by the fixed head 21 and the detachable head B, respectively.

While I have herein shown and described

what I consider the preferred manner of carrying out my invention, the same is merely illustrative and I contemplate all changes and modifications which come within the scope of the claims appended hereto.

70

I claim:

1. In a swiveled connection of a body bolster and a truck bolster member of a railway car, the combination with a center pin extending through the body bolster and truck bolster members, said pin having a fixed head at one end; of a detachable head member composed of at least three separable sections secured to the other end thereof; and means embracing said sections to prevent lateral separation and removal thereof. 75

2. In a center pin locking arrangement for railway cars, the combination with a body bolster member and a truck bolster member, said members having aligned center pin receiving openings, one of said members having a pocket communicating with the pin receiving opening thereof, said pocket being laterally extended beyond the side wall of said opening; of a pin extending through said opening and having a head at one end having shouldered engagement with one of said members, a sectional head secured to the other end of the pin and having shouldered engagement with the other member, the sections of said head being engaged with the pin by entering the same within the laterally extended portion of the pocket, said sections when engaged with the pin being rotatable to dispose the same in locking relation with the side walls of the pocket, thereby preventing lateral removal of said sections; and means for closing said extended portion of the pocket. 85

3. In a railway car construction, the combination with a body bolster member; of a truck bolster member on which the body bolster member is swiveled; a pin extending through said members, said pin having a head at one end, of larger size than the pin receiving opening, the other end of the pin having a head of a diameter not greater than the pin receiving opening; a detachable sectional head member embracing said last named head of the pin; and abutment means surrounding said pin receiving opening embracing the sectional head member, to prevent separation of the sections thereof, said abutment means including a removable wall section. 105

4. In a center pin locking arrangement for railway cars, the combination with a body bolster member and a truck bolster member on which the first named member is swiveled; of a pin extending through said members, said pin having a head at the lower end, cooperating with abutment means on the truck bolster member, said pin having an annular shoulder adjacent the upper end thereof; a detachable sectional head member embracing the upper end of the pin and cooperating with the abutment means on the body bolster member, the 115

sections of said head closely embracing the pin and having in-turned flanges having shouldered engagement with said annular shoulder; and an upstanding abutment wall on the body bolster, surrounding the pin receiving opening thereof embracing the sectional head member, to prevent separation of the sections thereof, said wall having a section thereof removable to permit assembling 5 of said sections with the pin, and means for securing said removable wall section to one of said head sections.

5. In a center pin locking arrangement for railway cars, the combination with a body bolster member and a truck bolster member, said members having aligned center pin receiving openings and one of said members being provided with a pocket aligned with the center pin receiving opening thereof, said 10 pocket having an annular side wall including a fixed wall section and a removable wall section, said bolster having a seat for said removable wall section; a center pin accommodated in said pin receiving openings, said center pin 15 having a section thereof extending through said pocket, said last named section of the pin being provided with an annular shoulder; a detachable cylindrical head secured to the last named section of the pin, said head comprising a plurality of sections embracing the 20 pin, said sections having in-turned flange portions engaging with the shoulder of the pin, said sections being embraced by the annular side wall of the pocket and held against lateral separation thereby, said removable wall 25 section, when detached, permitting insertion of the sections of the head, said sections being laterally displaceable toward the pin in said seat to permit engagement of the flanges thereof beneath the shoulder of the pin and being rotatable bodily in said pocket to dispose said sections about said pin between the 30 pin and the side wall of the pocket, to prevent lateral separation of said sections of the head.

40 45 In witness that I claim the foregoing I have hereunto subscribed my name this 11th day of June, 1928.

WILLIAM H. MINER.
